United States Patent Office.

ALBERT H. JOHNSON, OF HARTFORD, CONNECTICUT.

Letters Patent No. 77,493, dated May 5, 1868.

IMPROVEMENT IN BOSOM-PADS.

The Schedule referred to in these Letters Patent and making part of the same.

TO ALL WHOM IT MAY CONCERN:

Be it known that I, ALBERT H. JOHNSON, of the city and county of Hartford, in the State of Connecticut, have invented certain new and useful Improvements in a Combined Spring-Base and Air-Pad for Dress-Bosoms; and the following is a full, clear, and exact description of the same, reference being had to the accompanying drawings, making a part of this specification, in which—

Figure 1 represents the in or under-side view of a dress-bosom, showing the springs forming the base for the air-pads to rest upon.

Figure 2 shows my improvement as applied to a person.

Figure 3 shows a plan of the spring as applied for use.

Figure 4 is an edge view of the springs folded together for packing.

Figure 5 represents a section across the air-pad and spring.

Figure 6 is a side view of a cross-spring.

Figure 7 is a plan of the same with semicircular bearings.

The object of my invention is to form dress-bosoms that can be varied in size at the will of the wearer, and to prevent the air-pads when inflated from pressing hard upon the breasts, so as to be uncomfortable or oppressively hot in warm weather.

My invention consists in the mode of constructing a spring-base, and the manner of applying the same to and in combination with elastic air-pads for ladies' dress-bosoms.

To enable others to make and use my invention, I will describe it more fully, referring to the drawings, and to the letter marked thereon.

The base for supporting air-pads for dress-bosoms, to be worn by ladies who are spare in flesh, to whom nature has not provided a suitable or the desired fullness or rotundity of the thorax or bust, I make of spring-steel, or high hard-rolled brass, or of whalebone. The springs *a a* may be two, three, or more in number, they having steps or little pads, *b b b*, secured to the ends of the springs *a a*; or the steps *c c c* may be bars or crescents, as seen in fig. 7. The springs *a a* are curved as much as is desirable, and are secured together by a rivet, *e*, in the centre, so that they may be jacked or folded up together, for packing up for carrying in a trunk, or packed in a mass for transportation. On the under side of the cloth which forms the bodice *A*, may be secured a series of pockets, *d d d d*, for the pads *b b b* to be put into, to hold the springs *a a* directly under the air-pads *B B*, which may be made of oiled silk, elastic rubber cloth, or any other material in which air can be confined. The air-pads *B* may be made on to the front of the bodice permanent, or they may be made separate so that they can be attached or detached at pleasure, or they and the springs may be put together, and worn without being fastened to a bodice, as seen in fig. 5. When three or more springs are used for the support, they may be very light, their object being to keep the air-pads from pressing on the breasts, so as to cause too much heat in warm weather, as is the case with all kinds of padding worn which fits down closely on the person, so that it is regarded very essential to the comfort of the wearer to have the circulation of air between the padding and that part of the person on which it is worn. Dresses may be made with a space or pockets between the linings, in which my improved spring-base air-pads may be placed, and worn without any other mode of attaching them to the person, or they may be attached to a corset, and worn in the usual manner, and, in either case, be so that they can be removed readily for changing the apparel, or for having it washed and done up. The air-pads may be provided with a flexible tube, and suitable appliances for inflating, so that any desired degree of fullness or rotundity can be given, while the pressure upon the breasts is not increased or even felt, and in hot weather be kept cool and comfortable, the space under the springs being sufficient to ventilate the bosom, and give plenty of room for respiration—a condition most desirable at all times, and especially so for ladies in large assemblies, or when they wish to appear to good advantage before an audience, or entertain company.

Thus it will readily be seen that my improvement in the mode of constructing springs, and the manner of

attaching them so that they may be readily detached, and combining them with an elastic or air-bosom, aids the fair sex in restoring in some good degree to them what by nature or accident has been denied them, and at the same time the spring-base provides the means of keeping the person as cool and comfortable as if there were no "false pretense," and nothing to prevent the escape of perspiration. False bosoms constructed of other fabrics than those in which air can be confined, cannot easily be varied in size, so that often they do not serve the purpose of fitting dresses, and are often so compressed as to be very uncomfortable to the wearer; and air-bosoms which are secured to a rigid base are also not pleasant or agreeable to the wearer, they having been tried for several months, and all of the objections above enumerated have been found to exist. By my arrangement and combination of the spring-base and air-pad, all of the above-described objections are entirely remedied.

What I claim as my invention, and desire to secure by Letters Patent, is—

In combination with an inflated elastic bosom-pad, the supporting-springs *a a*, arranged as herein shown and described, and for the purposes specified.

In testimony whereof, I hereunto set my hand in the presence of—

A. H. JOHNSON.

Witnesses:

S. ROCKWELL,

C. L. JOHNSON.
